CULTIVATOR TINE SUPPORT

Ary van der Lely, 10 Weverskade,
Maasland, Netherlands

Filed Oct. 4, 1974, Ser. No. 512,047

Term of patent 14 years

Int. Cl. D15—03

U.S. Cl. D40—1 E

FIG. 1

FIG. 2

FIG. 3

FIG. 5

FIG. 4

FIG. 6

FIG. 1 is a side view of a cultivator tine support embodying my new design,

FIG. 2 is an elevation, viewed in the direction of arrow II in FIG. 1,

FIG. 3 is a side elevation viewed in the direction of arrow III in FIG. 1,

FIG. 4 is fragmentary part of an elevation, viewed in the direction of arrow IV in FIG. 3,

FIG. 5 is a cross-section along the line V—V in FIG. 4, and

FIG. 6 is a perspective view of the tine support embodying my new design.

I claim:

The ornamental design for a cultivator tine support, substantially as shown and described.
